UNITED STATES PATENT OFFICE.

FRIEDRICH HUNGER, OF CLEVELAND, OHIO, ASSIGNOR OF ONE-HALF TO
SOLOMON SCHMUCK, OF SAME PLACE.

RECLINING-CHAIR.

SPECIFICATION forming part of Letters Patent No. 325,248, dated September 1, 1885.

Application filed July 3, 1885. (No model.)

To all whom it may concern:

Be it known that I, FRIEDRICH HUNGER, of Cleveland, in the county of Cuyahoga and State of Ohio, have invented certain new and useful Improvements in Reclining-Chairs; and I do hereby declare the following to be a full, clear, and exact description of the invention, such as will enable others skilled in the art to which it pertains to make and use 10 the same.

My invention relates to improvements in reclining-chairs in which the back, arms, and arm-posts are hinged in the usual manner, with an extension-brace in the form of a sector secured to the arm and arm-post for holding the parts in the desired position, to the end that a strong, simple, and ornamental device is had at a small initial cost.

With this object in view my invention consists in certain features of construction and in combination of parts hereinafter described, and pointed out in the claims.

In the accompanying drawings, Figures 1 and 2 are side elevations of my improved chair, respectively showing the back in an upright and in an inclined position. Fig. 3 is an enlarged view in perspective of the extension-bar. Fig. 4 is a view in perspective of the plate G. Fig. 5 is an elevation in transverse section on the line $x x$, Fig. 3.

A represents the chair-back, that is hinged to the rear portion of the seat B. C are the arm-posts, that are hinged to the side and front portions of the seat. D are the arms, and are hinged to the arm-posts at a and to the back at a' .

The parts E and F form an extension-brace in the form of a sector, whose center is the axis of the hinge d . The female part E has a longitudinal groove, E', in the upper face of which operates the male part F. The lower wall of the part E has a series of holes, e , opening into the groove E', that receives the hook end f of the part F. The part E has a slotted arm, E'', that is secured to the post C, as is also the lower end of the part E. The part F is pivoted at f' to ears g of the plate G, the latter being secured to arm D. A hand-lever, F', integral with the part F, ex-

tends forward along under the arm D in 50 position to be grasped by the fingers when the hand is resting on the arm D. By pressing against the under side of the lever F' the part F is tilted, and the hook end f is withdrawn from the holes e , and, at the 55 same time, with the hands in position grasping the arms D, the back of the chair may be brought to the desired inclination, when, by releasing the lever F', the hook end of the part F is depressed by gravity, and by 60 engaging a hole, e , locks the device and secures the back. The metal parts are cast so that little fitting is required other than such finishing as may be desired for ornamentation.

By reason of the circular form of the extension-braces they add to rather than detract from the beauty of the chair, and by reason of the larger dimensions of the braces in a radial direction excessive strain on the 70 hinges d is avoided.

What I claim is—

1. In a reclining-chair, the combination, with the chair-back and arm-posts, respectively hinged to the seat and to the arms, 75 substantially as indicated, of extension-braces in the form of a sector, the parts of the brace made male and female, the one portion of the brace being secured to the arm-post, and the other portion pivoted to the arm, the two parts of the brace having holes, projections, or depressions for mutually engaging the pivoted parts of the brace, with a hand-lever arranged under the respective arms for operating the extension-bar, substantially as 80 set forth.

2. In a reclining-chair, the combination, with a seat, back, arms, and arm-posts, the parts hinged to each other, substantially as indicated, of an extension-brace in the form 90 of a sector, having its center at the axis of the hinge d , the parts made male and female, forming a slip-joint, and provided, respectively, with suitable holes, depressions, or projections for engaging each other, the one 95 part of the brace being secured to the arm-post and the other portion of the brace being pivoted to the arm, a hand-lever for ele-

vating the pivoted part to disengage it for
tilting the chair-back, and so arranged that
the parts of the brace, when left free, will
engage each other by means of the gravity
5 of the pivoted portions, substantially as set
forth.

In testimony whereof I sign this specifica-

tion, in the presence of two witnesses, this 27th
day of June, 1885.

FRIEDRICH HUNGER.
